UNITED STATES PATENT OFFICE.

BYRON PHELPS, OF SEATTLE, WASHINGTON, ASSIGNOR OF ONE-HALF TO
THEODORE NELSON, OF CHICAGO, ILLINOIS.

LOCK.

SPECIFICATION forming part of Letters Patent No. 660,736, dated October 30, 1900.

Application filed January 27, 1900. Serial No. 2,958. (No model.)

To all whom it may concern:

Be it known that I, BYRON PHELPS, a citizen of the United States, residing at Seattle, King county, Washington, have invented certain new and useful Improvements in Locks, of which the following is a full, clear, and exact description.

My invention relates to improvements in locks and latching mechanism; and my object is to improve the construction of the same.

One of my particular objects is to provide a lock having latch mechanism and side plates on two opposite sides of said mechanism, a spindle passing through one of said plates and connected with the latch mechanism to operate the same, the plate on the other side of said mechanism being adjustable to and from said latch mechanism, a spindle carried by said adjustable plate, and a longitudinally-adjustable latch-operating connection between said latch mechanism and latter spindle, whereby said spindle and plate may be adjustable to and from said latch mechanism.

In the preferred embodiment of my invention shown in the drawings, Figure 1 represents a plan view, parts being broken away, of a lock embodying my invention. Fig. 2 represents a side view of the same, the left-hand side plate having been removed, looking from left to right and parts being in section. Fig. 3 represents the same view as Fig. 2, but with the bolt thrown back by the thumb-nut. Fig. 4 represents a detail showing the manner in which the latch mechanism is operated by the adjustable spindle.

In the embodiment shown in the drawings I have applied my invention to a lock which is adapted to be inserted in a notch in the stile of a door of the general construction claimed in my former patent, No. 626,340, dated June 6, 1899.

In the drawings, A represents the main frame, which I preferably use; but it will be obvious that the same is not necessary in some cases. This frame preferably supports the latch mechanism and may have two side plates B and C and a face-plate D, through an opening in which works a latch-bolt or head D'. Pivoted to this latch-bolt is in this embodiment a yoke E, preferably having two legs e e', each of which may be provided with

a foot e² e³. A spindle-bearing F may be attached to the main frame and inclose a spindle G, having a knob g thereon. This spindle is connected with the latch mechanism to operate the same, preferably by a roll-back H, the ends of which stand in front of the feet e² e³ on the yoke, so that when the spindle is rotated in either direction the latch-bolt will be thrown back. The spindle is preferably hollow at its inner end, as shown in Figs. 2, 3, and 4, and I prefer to pass the roll-back completely through the spindle, as shown, for the purposes which will be described hereinafter. The side plate C may be made adjustable to and from the latch mechanism and in this embodiment to and from the main frame also, as claimed in my said former patent.

To throw back the bolt from the side of the door on which the adjustable plate is located, I provide a rotatable spindle, carried by said adjustable plate, and a latch-operating connection between said spindle and latch mechanism, which allows the spindle to be longitudinally adjusted with respect to said mechanism. In this embodiment I have dispensed with a projecting spindle and knob, and in place thereof I have formed the spindle as a part of a preferably pin tumbler-lock passing through and attached to the side plate C. In this embodiment the rotatable key-barrel L of the pin tumbler-lock constitutes the spindle. The casing of this lock is preferably cylindrical and fits a hole in the frame A to guide the plate C, and I may also provide an internally-threaded lug c on the side plate, which may receive a screw c', passing through the frame, so as to draw the plate C inward against the stile of the door and fasten the plate in any position desired. Between this spindle and the latch-operating mechanism—that is, operatively connecting the same—is an adjustable connection, so that when the entire lock is inserted in the notch in the stile of a door the side plate may be adjusted to any thickness of door, yet the spindle L will be operatively connected with the latch mechanism. I am aware that the manner of making this connection may be widely varied; but I have in the present embodiment provided a pair of forward projections l l, at

tached to the spindle L and forming a fork, (shown in section in Fig. 2, 3, and 4,) which may stand on each side of the roll-back H. The projections l l, together with that part of the roll-back H which is engaged by said projections, form in this embodiment the latch-operating connection between the latch mechanism and the spindle, and as the fork can be moved back and forward while still in closing said part of the roll-back the parts of the connection are adjustable with relation to each other. When a key is inserted in the key-barrel, the key-barrel may be rotated until one of the projections l is brought into engagement with the roll-back, and the same can then be moved to throw back the latch, as shown in Fig. 4.

As shown in Figs. 2, 3, and 4, I have formed the projections l l so that when in their normal position (shown in Figs. 1, 2, and 3) they will permit of the rotation of the spindle G far enough to throw back the latch without moving the spindle L. This is desirable in the present embodiment, because the key-barrel is normally locked in position until a key is inserted therein, and therefore provision should be made for the movement of the latch mechanism without rotating said barrel. The roll-back H in this embodiment performs the additional function of holding the spindle F in place, because said roll-back rests against one side of the frame, as shown in Fig. 1.

To throw back the latch and lock the same in its retracted position, I have provided a dog S, to which is connected a thumb-nut S', by the rotation of which thumb-nut the cam T on the dog is rotated, which will come in contact with a projection T' from the yoke 40 and push the same back from the position shown in Fig. 2 to that shown in Fig. 3.

I am aware that very many changes may be made in the construction heretofore shown and described without departing from the spirit of my invention, and I therefore do not wish to limit myself to the embodiment herein disclosed.

What I claim is—

1. In a lock in combination, latch mechanism, a side plate at one side of said latch mechanism, a spindle passing through and rotatable in said side plate and connected with said latch mechanism to operate the same, a plate at the other side of said latch mechanism, said plate being adjustable to and from said latch mechanism, a rotatable spindle carried by said adjustable plate and held from longitudinal movement therein and a latch-operating connection between said latch mechanism and latter spindle, parts of which connection are adjustable with relation to each other by the movement of said adjustable plate, whereby said latter spindle and plate may be adjusted to and from said latch mechanism.

2. In a lock in combination, a main frame, a side plate on one side of said frame, latch

mechanism carried by said frame, a spindle passing through and rotatable in said side plate and connected with said latch mechanism to operate the same, a plate at the other side of said frame, said plate being adjustable to and from said main frame, a rotatable spindle carried by said adjustable plate and held from longitudinal movement therein, and a latch-operating connection between said latch mechanism and latter spindle, parts of which connection are adjustable with relation to each other by the movement of said adjustable plate, whereby said latter spindle and plate may be adjusted to and from said frame.

3. In a lock in combination, latch mechanism, a side plate at one side of said mechanism, a spindle passing through and rotatable in said plate and connected with said latch mechanism to operate the same, a plate at the other side of said latch mechanism, said latter plate being adjustable to and from said latch mechanism, key-operated means carried by said adjustable plate and having a rotatable part, and a latch-operating connection between said rotatable part and latch mechanism, parts of which connection are adjustable with relation to each other by the movement of said adjustable plate, whereby said plate and key-operated means may be adjusted to and from said latch mechanism.

4. In a lock in combination, a main frame, a side plate at one side of said frame, latch mechanism carried by said frame, a spindle passing through and rotatable in said plate and connected with said latch mechanism to operate the same, a plate at the other side of said frame, said latter plate being adjustable to and from said main frame, a key-operated lock carried by said adjustable plate and having a rotatable barrel, and a latch-operating connection between said barrel and latch mechanism parts of which connection are adjustable with relation to each other by the movement of said adjustable plate whereby said plate and lock may be adjusted to and from said frame.

5. In a lock in combination, latch mechanism, a side plate at one side of said latch mechanism, a spindle passing through and rotatable in said plate and connected with said latch mechanism to operate the same, a plate at the other side of said latch mechanism, said latter plate being adjustable to and from said latch mechanism, a key-operated lock carried by said adjustable plate having a rotatable barrel and a latch-operating connection between said barrel and latch mechanism including a forward projection on said barrel parts of which connection are adjustable with relation to each other by the movement of said adjustable plate whereby said plate and lock may be adjusted to and from said latch mechanism.

6. In a lock in combination, a latch mechanism including a roll-back, a side plate at one side of said latch mechanism, a spindle

- passing through and rotatable in said plate and connected with said latch mechanism to operate the same, a plate at the other side of said latch mechanism, said latter plate being 5 adjustable to and from said latch mechanism, a key-operated lock carried by said adjustable plate and having a rotatable barrel, and a latch-operating connection between said barrel and latch mechanism including a 10 fork on said barrel adapted to inclose said roll-back whereby said plate and lock may be adjustable to and from said latch mechanism. 7. In a lock in combination, a main frame, a side plate at one side of said frame, latch 15 mechanism carried by said frame including a roll-back, a spindle passing through and rotatable in said plate and connected with said roll-back to operate the same, a plate at the other side of said frame, said plate being 20 adjustable to and from said main frame, a guide for said plate between the same and said frame, a pin tumbler-lock carried by said adjustable plate and having a rotatable key-barrel, and a latch-operating connection be- 25 tween said barrel and latch mechanism, including a fork on said barrel adapted to loosely inclose said roll-back so as to allow for the rotation of said opposite spindle without moving said key-barrel, said connection allowing said plate and lock to be adjusted 30 to and from said frame. 8. In a lock in combination, latch mechanism, a side plate at one side of said latch mechanism, a spindle passing through and rotatable in said side plate and connected with 35 said latch mechanism to operate the same, a plate at the other side of said latch mechanism, said plate being adjustable to and from said latch mechanism, a rotatable spindle carried by said adjustable plate and held from longitudinal movement therein, and a latch-operating connection part of which is carried by the latter spindle whereby said latter spindle and plate may be adjusted to and from 40 said latch mechanism. 45

Signed at New Britain, Connecticut, this 25th day of January, 1900.
